UNITED STATES PATENT OFFICE.

HENRY C. STRACK, OF OWEGO, NEW YORK, ASSIGNOR OF TWENTY-FOUR ONE-HUNDREDTHS TO WALLACE D. STRACK AND TWENTY-FOUR ONE-HUNDREDTHS TO HENRY D. STRACK, OF BROOKLYN, NEW YORK.

GRINDING-MILL.

1,111,770.

Specification of Letters Patent. Patented Sept. 29, 1914.

Application filed July 28, 1913. Serial No. 781,689.

To all whom it may concern:

Be it known that I, HENRY C. STRACK, a citizen of the United States, and a resident of Owego, Tioga county, State of New York, have invented a certain new and useful Improvement in Grinding-Mills, of which the following is a specification.

This invention is chiefly intended to be applied to mills of the type shown in my Patent No. 1,074,299, granted September 30, 1913.

The objects I have in view are to increase the grinding efficiency of the mill, to eliminate waste, reduce labor and shorten the time incident to the grinding operation.

Another object is to relieve the parts from excessive strain, and avoid the beating of excessive quantities of air into the material, and avoid spilling the material over the rim 20 of the shell.

In the drawings: Figure 1 is a vertical section of the preferred embodiment of the invention. Fig. 2 is a top view of the same device. Fig. 3 is a side elevation of the 25 rotary grinders showing the location and position of the plow thereon. Fig. 4 is a detail showing a top view of the scrapers and showing the shaft in cross-section. Fig. 5 is a top view of the lower grinder showing 30 the shaft and keys in cross-section. Fig. 6 is a bottom view of the upper grinder showing the shaft in cross-section. Fig. 7 is a bottom view of the lower grinder showing 35 the shaft in cross-section. Fig. 8 is a top view of the shell. Fig. 9 is a vertical section of a modification. Fig. 10 is a top view of the shaft and spiral conveyer of the same; and Fig. 11 is a top view of a ring 40 for holding the scrapers in engagement with the shaft.

Referring to the drawings, the inclosing casing 1 is made of suitable material, and of the proper size. It is attached to a shell 2, the walls of which are preferably inclined, as shown, forming grinding surfaces. The base of the shell opens into a discharge pipe 27 which is equipped with a valve 26. Within the casing is a rotary grinder 4, which has rotating means, and also preferably has conveying means within it. All of the preceding described parts are preferably made like the equivalent parts which are

disclosed in my Patent 1074299. In addition to the grinder 4, there is a grinder 3. Only one grinder, 3, is illustrated, but the 55 invention is not limited to a single grinder 3.

The grinder 3 rotates within the shell and is adapted to grind the material between its lower face and the shell 2, and to assist in the grinding of material between its upper face and the grinder 4. The grinder 3 is preferably made in the shape of a disk with a convex bottom face and a concave top face. This convex bottom face is best provided with grooves 32 to assist in the 60 grinding operation. The upper face of the grinder is preferably concave so that the material contained within the shell will flow from the periphery to the center of the grinder. The grinder 3 engages with the 65 shaft 5 and is rotated by it by any suitable means, such as feathers 31. The shank of this shaft goes through an opening in the shell 2 and is rotated by any suitable means, such as by the pulley 25. This pulley is 70 turned by means of a belt (not illustrated). It is preferably rotated at a relatively high rate of speed. In order to prevent leakage of the material through the opening in the shell, a gland 24 is provided. This gland 75 compresses and retains in position suitable packing material 23. The shaft 5 is provided with a spiral or screw-thread to act as a conveyer in the same manner as the conveyer described in Patent 1,074,299, and 80 also to act as an additional grinding means. 85

The grinder 4 rotates within the shell in an opposite direction from that of the grinder 3. It is adapted to grind material between its lower face and the upper face 90 of the grinder 3. The grinder 4 is preferably made in the shape of a cylinder, with a conical bottom face. This conical bottom face is best provided with grooves 32 to assist in the grinding operation. The upper 95 face of the grinder 4 is preferably conical so that the material contained within the shell will freely flow from the center toward the periphery of the grinder. The grinder 4 is supported upon a shaft 40. This shaft is rotated by any suitable means, such as by the bevel gears 7 and 8. The rate of speed is preferably much less than that of the shaft 5 and lower grinder 3. 100

For the purpose of supporting the shaft 40 a yoke 6 is provided. The yoke is held to the top of the outer casing by any suitable means, such as hinges 20, 20, bosses 19, 19 and bolts 15, 15.

The material which is being ground between the grinding surfaces passes to the bottom of the shell 2, and means are provided for circulating this material from below the grinders to above the same, so that it may be re-ground as many times as desired, in the manner set forth in my Patent 1074299. This means includes a passage which is preferably located within the shaft 40. The ground material is conveyed through this passage by suitable conveying means which are preferably located within the passage. The devices for accomplishing this are as follows: The passage extends up through the grinders to a suitable distance above the same, near the top of the inclosing casing 1. The spiral or screw-threads of the shaft 5 elevate the material in the passage. An outlet opening 50 is made in the top of the passage through the shaft 40.

To assist in the grinding operation, the shaft 5 is best made tapered, and the opening in the shaft 40 is also best tapered, as shown. The spiral will grind material between it and the inner wall of the central opening. To adjust the pressure of the parts, a press-screw 28, on an arm 29, is provided.

For the purpose of preventing material from accumulating above the grinders, I provide a plow 17. This plow is carried by the grinder 4, and rotates with it, as shown. The outer edge of the plow is in close engagement with the inner walls of the inclosing casing and the shell. In order to assist in the downward flow of the material, the plow is preferably inclined, as shown in Fig. 3. The arrows in Fig. 3 illustrate the directions of rotation of the grinders 3 and 4 in the embodiment chosen for illustration. It is obvious that two or more plows may be used, and that they may be carried by the grinder 3 instead of the grinder 4. The advantage of rapid grinding and elevating of the material, without the spilling of the material over the rim of the shell, is obtained by rotating the upper grinder 4 that carries the plow slowly in one direction, and rotating the grinder 3 between the upper one 4 and the bottom of the shell rapidly in the other direction.

For the purpose of preventing the accumulation of material upon the top of grinder 4 and upon the outside of the shaft 40, I employ scrapers 11, 11. These scrapers extend outward from the shaft 40 to the periphery of the grinder 4. These scrapers are provided with vertical shanks which engage with the shaft 40. For the purpose of supporting the scrapers in position, they are

provided with rings 22. These rings surround the shaft 40, and have adjusting means 10 for holding the scrapers in contact with the shaft. The scrapers are rotated by any suitable means, such as by the pulley 12 and belt 9, and preferably in the opposite direction to the shaft 40. The scrapers are held down on the grinder 4 by means of a spring 14 attached to the yoke 6. The spring engages with an annular ring 21, which in turn engages with the pulley 12.

Fig. 9 and Fig. 10 illustrate a modification of the invention in which a single grinder is used, and a different arrangement of the spiral conveyer for grinding purposes is employed. A squared tapered shaft 34 is employed. The straight spiral conveyer 33 is divided vertically into two parts. These parts have grooves on their inner faces that are tapered and shaped to accommodate and coöperate with the taper and shape of shaft 34. The inclined sides of the shaft pressing against the inclined faces of the grooves force the vertical halves forming the spiral conveyer outward horizontally and cause them to engage the inner face of the passage and thus effect grinding results when rotating. A clamp 35 loosely grips an annular ring on the bottom of the shaft 34, the degree of pull on the shaft to expand the spiral conveyer being controlled by a weight attached to an arm, as shown.

Having now described my invention, I claim:

1. A grinding mill having a casing with a fixed grinding surface; rotating superimposed grinders within the casing, means for rotating the grinders, said means rotating the grinders at different relative speeds.

2. A grinding mill having a casing with a fixed grinding surface; rotary superimposed grinders within the casing, and means for rotating the grinders in opposite directions to one another.

3. A grinding mill having a casing with a fixed grinding surface; rotary superimposed grinders within the casing, and means for rotating the grinders in opposite directions to one another at different relative speeds.

4. A grinding mill having a casing; a rotary grinder within the casing, a plow carried by the said grinder and rotating with it, a scraper engaging with the grinder and means for rotating the scraper independently of the grinder.

5. A grinding mill having a casing; rotary superimposed grinders within the casing, a hollow shaft for supporting the upper grinder, a conveyer within a hollow shaft for causing the material to pass through the hollow shaft from below the grinders to above the same, a shank on the conveyer, means on the shank for engaging with the lower grinder, means for rotating

the shank and the hollow shaft, and a plow carried by one of the grinders and rotating with it.

6. A grinding mill having a casing; rotary superimposed grinders within the casing, a hollow shaft for supporting the upper grinder, a conveyer within the hollow shaft for causing the material to pass through the hollow shaft from below the grinders to above the same, a shank on the conveyer, means on the shank for engaging with the lower grinder, means for rotating the shank and the hollow shaft, a scraper engaging with one of the grinders and means for rotating the scraper independently of the grinder.

7. A grinding mill having a casing; rotary superimposed grinders within the casing, a hollow shaft for supporting the upper grinder, a conveyer within the hollow shaft for causing the material to pass through the hollow shaft from below the grinders to above the same, a shank on the conveyer, means on the shank for engaging with the lower grinder, means for rotating the shank and the hollow shaft, a scraper engaging with one of the grinders, means for rotating the scraper independently of the grinder and a plow carried by one of the grinders and rotating with it.

8. A grinding mill having a casing; a rotary grinder within the casing, a scraper engaging with the grinder, and means for rotating the scraper independently of the grinder.

9. A grinding mill having a casing; rotary superimposed grinders within the casing, a hollow shaft for supporting the upper grinder, a conveyer within the hollow shaft

for causing the material to pass through the hollow shaft from below the grinders to above the same, a shank on the conveyer, means on the shank for engaging with the lower grinder, and means for rotating the shank and the hollow shaft.

10. A grinding mill having a casing and a rotary grinder therein, means for rotating the grinder, a hollow shaft associated with the grinder, a rotary conveyer within the hollow shaft and means for engaging the conveyer with the inner surface of the shaft to grind the material between the two said surfaces.

11. A grinding mill having a casing and a rotary grinder therein, means for rotating the grinder, a hollow shaft associated with the grinder, a rotary conveyer within the hollow shaft, means for engaging the conveyer with the inner surface of the shaft to grind the material between the two said surfaces and means for adjusting the engaging pressure of the conveyer and shaft.

12. A grinding mill having a casing and a rotary grinder therein, means for rotating the grinder, a hollow shaft associated with the grinder, a rotary conveyer within the hollow shaft, said conveyer being tapered and the opening in the shaft also tapered, and means for imparting relative longitudinal motion to the said conveyer and shaft for engaging the conveyer with the inner surface of the shaft to grind the material between the two said surfaces.
